UNITED STATES PATENT OFFICE.

MOSES BASSETT, OF CLEVELAND, OHIO.

SHADE AND CURTAIN BRACKET.

958,463.

Specification of Letters Patent. Patented May 17, 1910.

Application filed December 10, 1909. Serial No. 532,322.

To all whom it may concern:

Be it known that I, MOSES BASSETT, a citizen of the United States, residing at Cleveland, in the county of Cuyahoga and 5 State of Ohio, have invented certain new and useful Improvements in Shade and Curtain Brackets, of which the following is a specification.

This invention relates to a combined shade and curtain bracket, and has for its object to provide an improved device which will support both a shade roller and a curtain pole, the construction being such that it may be cheaply produced, mainly from sheet 15 metal cut and pressed to the necessary form.

The device is particularly adapted for attachment to the upper bar of the upper window sash, whereby the shade and curtain may be raised and lowered with the sash, so 20 as to facilitate ventilation.

An adjustment is provided for the shade brackets, to accommodate shades of different widths. An advantageous attaching device is also provided, whereby the brackets can 25 be easily and readily removed from the sash, to allow the upper sash to be lowered below the lower sash, when desired.

The invention is illustrated in the accompanying drawings in which—

30 Figure 1 is a perspective view of the invention as applied to a window. Fig. 2 is a section showing the means for connecting the shade roller fixture. Fig. 3 is a vertical section of the attaching socket. Fig. 4 is a front view of the socket.

Referring specifically to the drawings, 1 indicates the side facings of a window casting and 1^a the lintel thereof. The upper sash is indicated at 2.

40 Each bracket is made of a piece of sheet metal cut and stamped or pressed to form a front vertical part 4 having at the upper end thereof a lateral horizontal extension 4^a, a rear vertical part or shank 4^c, and a horizontal connecting part 4^b between the lower end of the vertical part 4 and the upper end of the shank 4^c. Both brackets are similarly constructed, except that they are made right and left.

45 50 Each bracket is attached to the upper bar of the sash by means of a sheet metal socket piece 6, attached to the sash by screws 11, and embossed or pressed out to form a space between the same and the sash to re-

ceive the flat shank 4^c which fits snugly 55 therein. At the upper edge the socket plate is notched or depressed as indicated at 6^a, and the horizontal part 4^b of the bracket rests in said depression, so that the upper surface of said horizontal part is flush with 60 the top edge of the socket piece. The socket piece is fixed to the sash bar so that its upper edge will contact with the lintel 1^a when the sash is closed, and the upper surface of the horizontal part 4^b will lie close or in contact with the bottom of the lintel. 65

The shade fixtures 7 and 7' are of ordinary construction, and are fastened to the front side of the arms 4^a by means of screws 5 in threaded holes 10 formed in said arms. A 70 series of holes are provided so that the fixtures may be set at various positions according to the length of the shade roller. At the extremities of the arms 4^a holders for the curtain pole are attached. Each holder may 75 consist of a piece of wire bent at its rear end and fastened by rivets 9 or the like, and curved at the outer end as indicated at 8 to support the pole. These holders for the pole project forwardly beyond the shade fixtures, 80 so that the curtain will be supported in front of the shade and will not interfere therewith.

It is obvious that when the sash is lowered the shade and curtain will be also lowered, 85 so that the upper part of the window may be opened for ventilation if desired, without danger of blowing the shade or curtain out of position. The parts may be readily removed by lowering the sash and slipping 90 the shanks 4^c out of the sockets, and said sockets being flat and thin will allow the upper sash to pass the lower sash of an ordinary window. But when the upper sash is closed the brackets are held in the sockets 95 and cannot be accidentally dislodged therefrom.

What I claim as new is:—

1. A shade support comprising a bracket having at one end an upstanding part and 100 a horizontal arm projecting laterally from said part, means at the other end of the bracket to attach the same to a frame, and a fixture attached to said horizontal arm and adjustable thereon to vary the lateral position of the fixture.

2. A shade and curtain support comprising a bracket made of a strip of sheet metal

having a laterally extending arm at its outer end, and bent to form an upright part from which said arm projects, a horizontal rearwardly extending part at the lower end of 5 said upright part, and a depending shank at the rear end of said rearwardly extending part, a shade fixture attached to said arm, a curtain pole holder attached to the outer

end of said arm, and means engaging the shank to attach the bracket to a frame. 10

In testimony whereof, I hereby affix my signature in the presence of two witnesses.

MOSES BASSETT.
